O. B. MORSE, OF YORK, PENNSYLVANIA.

STOCK AND DIES.

1,108,346.

Specification of Letters Patent. Patented Aug. 25, 1914.

Application filed December 4, 1913. Serial No. 804,760.

To all whom it may concern:

Be it known that I, HARMAN K. DRAWBAUGH, a citizen of the United States, residing at York, in the county of York and State 5 of Pennsylvania, have invented certain new and useful Improvements in Stocks and Dies; and I do declare the following to be a full, clear, and exact description of the invention, such as will enable others skilled in 10 the art to which it appertains to make and use the same.

This invention relates to improvements in stocks and dies and the primary object of 15 the invention is to provide a device of this character so constructed as to allow it to be quickly and easily removed from the work after the thread has been cut thereon, without the necessity of unscrewing the device and causing the teeth of the same to pass 20 over the completed thread.

A secondary object is to provide means for adjusting the dies for application to different sized pipes or shafts.

Still another object is to so construct the 25 cutting edges of the dies that they will form no shoulder at the termination of the thread.

With the above objects in view, the invention resides in certain novel features of construction and combination herein described 30 and claimed, and shown in the drawings wherein:—

Figure 1 is a plan view of my improved die stock showing the dies arranged in operative position therein; and Fig. 2 is a side 35 elevation partly in section of the parts shown in Fig. 1.

In the embodiment illustrated in the drawings, my improved device is shown as comprising in general, a die stock 1, dies 2 slidably mounted thereon and locking members 3 for holding said dies in a projected and operative position.

The die stock is in the form of a flat metal plate provided with parallel die guides 4 on 45 its upper face, with the usual depending sleeve or apron 5 and sockets 6 for the reception of operating handles and with guides 7 near its opposite ends, the guides 7 being here shown in the form of lugs.

50 The above mentioned dies 2 are provided with the usual cutting teeth 8 and said dies are slidably mounted between the guides 4 by means of set screws 9 passing through slots 10 in the dies and into the stock 1.

I preferably provide stiff coil springs 11 between the heads of said set screws and washers 12 which overlie said slots. As clearly shown in Fig. 1, the dies 2 and the guides 4 are provided with indicators 13 which are adapted to align when the dies are in the 55 proper position to cut threads on standard sized pipes.

The guides 7 on the die stock 1, are provided with longitudinal bores in which sleeves 14 are slidably and rotatably mounted. These sleeves 14 are provided on their inner ends with shoulders or projections 15 adapted to be held normally in contact with cams 16 preferably formed on the inner ends of the guides 7. The sleeves 14 are internally threaded for the reception of screws 17, which as shown, project beyond the opposite ends of said sleeves and have their inner ends contacting with the outer faces of the dies 2. Operating handles 18 have 65 their inner ends threaded on the screws 17 and are clamped between the outer ends of the sleeves 14 and lock nuts 19. I also provide coil springs 20 which are disposed between the handles 18 and the guides 7 and 70 surround the outer projecting ends of the sleeves 14, said springs being adapted to normally hold the shoulders 15 in contact with the cams 16 and to withdraw the sleeves 14 and the screws 17 when the handle 18 is 75 actuated in the proper direction.

By the above described construction, I am 80 enabled to thread the ends of pipes or shafts in the usual manner and when said pipes or shafts have been threaded to the proper point, I may operate the handles 18 which, through the action of the sleeves 14, the shoulders 15, the cams 16 and the springs 20 will cause the inner ends of the screws 17 to disengage the dies 2. This leaves the dies 90 2 free to move outwardly so that their cutting teeth 8 will disengage the newly formed threads and the entire device may then be removed without the usual operation of unscrewing the device from said threads.

100 By reference to Fig. 2, it will be seen that I bevel the lower ends of the cutting faces of the dies and by so doing no abrupt shoulders will be left on the threaded article where the threads terminate. The formation of these cutting edges also forces the dies away from the article threaded and 105 disengages the cutting teeth from the

thread, as above mentioned, when the latches 3 are withdrawn by the operating mechanism above described.

In order to facilitate the easy operation 5 of the device when cutting threads, I preferably grind the outer beveled faces of the dies 2 on an arch as shown at 21. By so doing, I find that whereas with the ordinary dies and stocks, two men are required to 10 thread a two inch pipe, with the dies ground in this manner one man is enabled to do the same work.

Although I have described my invention with considerable minuteness, I do not wish 15 to be limited to details other than those amplified in the appended claims.

What I claim as my invention is:—

1. A device of the character described comprising a die stock, a die movably carried thereby, a guide and a cam carried by 20 said stock, a sliding element engaged with said guide and contacting with said die, a shoulder on said sliding element engaging said cam, and means for rotating said sliding element to project the same into contact with said die.

2. A device of the character described comprising a die stock, a die movably carried thereby, a guide on said stock, a cam 30 on said guide, a sleeve rotatably and slidably mounted in said guide, a shoulder on said sleeve in contact with said cam, a screw threaded through said sleeve and bearing against said die, means for retaining said shoulder in contact with said cam for holding 35 said screw in contact with said die, and

means for rotating said sleeve to move said screw out of contact with said die.

3. A device of the character described 40 comprising a die stock, a die movably carried thereby, a guide on said stock, a cam face on one end of said guide, a sleeve slidably and rotatably mounted in said guide, a projection on said sleeve, a spring for holding said projection in contact with said cam 45 face, a screw threaded through said sleeve and in contact with said die, and a handle for rotating said sleeve and withdrawing said screw from contact with said die through the action of the cam, the projection and the spring.

4. A device of the character described 50 comprising a die stock, a die movably carried thereby, a guide on said stock, a cam face on one end of said guide, a sleeve slidably and rotatably mounted in said guide, and projecting beyond the opposite ends thereof, a projection on one end of said sleeve, a screw threaded through said sleeve 55 and projecting beyond the opposite ends thereof and contacting at one end with said die, a handle on said screw, a lock nut for forcing said handle into contact with one end of said sleeve, and a coil spring on said sleeve between said guide and said handle.

In testimony whereof I have hereunto set my hand in presence of two subscribing witnesses.

HARMAN K. DRAWBAUGH.
